UNITED STATES PATENT OFFICE.

ALPHONSE CÔTÉ, OF EEL RIVER, NEW BRUNSWICK, CANADA.

TENSIONING DEVICE FOR SAWS.

Application filed June 12, 1922. Serial No. 567,770.

To all whom it may concern:

Be it known that I, ALPHONSE CÔTÉ, subject of the King of Great Britain, residing at Eel River, in the Province of New Brunswick, Canada, have invented certain new and useful Improvements in Tensioning Devices for Saws; and I do hereby declare that the following is a full, clear, and exact description of the invention, such as will enable others skilled in the art to which it appertains to make and use the same.

This invention relates to new and useful improvements in tensioning devices for saws, and is particularly applicable to buck and frame saws.

The primary object of the invention is to provide means of the character indicated above that is durable, efficient and readily applicable to a saw frame.

A further object of the invention resides in the construction of a frame that decreases the action of moisture upon the saw blade. In a frame composed entirely of wood, all the moisture absorbed by the wood can be conducted through the frame to the saw blade upon which it has a detrimental effect. In the present invention, a portion of the frame consists of metal, which is incapable of conducting moisture to the blade, and which further tends to avoid warping of the frame.

Further objects and advantages of the invention will appear as the description continues.

A preferred embodiment is shown in the accompanying drawings in which:

Figure 1 is a side elevation of a buck saw having my device applied thereto;

Figure 2 is a plan view of Figure 1;

Figure 3 is a detail perspective view; and,

Figure 4 is a section taken on the line 4—4 of Figure 1.

The frame of the saw consists of a pair of side bars 1, 2 pivoted to the ends of a body portion 3. The body portion includes a top 4 and connecting straps 5, a pair of which is secured to each end of the top and two opposite sides of the side members 1, 2. The union between a pair of connecting straps 50 and a side bar consists of a bolt 6 passing through the side member and the straps,

held in place by a nut 7, thus providing a pivotal connection between the straps and the sides. A ratchet or toothed member 8 is secured to one end of the top of the frame by a plurality of screws or similar devices 9, and is intended for permanent position in this relation. A similar device 10 is secured to the other end of the top by means of an integral portion embracing the top and a pair of screws 11. This member may be readily moved from one position to another, because of the small number of fastening members employed.

Upon each side member is pivoted a link 12 by means of an eyelet 13, whereby the link may be raised out of engagement with the notch member. It will readily be observed that the tension on the saw blade is governed by the particular notches in which the links 12 are inserted. In the event that an extraordinary long saw blade is used, the notched member 12 may be readily moved inwardly upon the frame top, by manipulation of the screws.

Although a particular form of the invention has been illustrated and described, it is to be understood that various details of construction may be made within the scope of the appended claims.

Having thus fully described the invention, what I claim as new and desire to protect by Letters Patent is:—

1. A saw frame comprising a pair of side bars, a top member between and spaced from said bars, metallic straps connecting said top with the bars, the straps being pivoted to the bars, toothed members fixed to the ends of the top, and links attached to the side members and adjustably engageable with the toothed members.

2. A saw frame comprising a pair of side bars, a top member between and spaced from said bars, metallic straps connecting said top with the bars, the straps being pivoted to the bars, toothed members adjustably fixed to the ends of the top, and links attached to the side members and adjustably engageable with the toothed members.

In witness whereof I have hereunto set my hand.

ALPHONSE CÔTÉ.
